Hanson & Howson

UNITED STATES PATENT OFFICE

HUGH WILLIAMSON KELLY, OF WOODBRIDGE, NEW JERSEY

METHOD OF MAKING TRACK TORPEDOES

Application filed May 25, 1929. Serial No. 365,987.

This invention relates to a track torpedo or similar device, and is more particularly concerned with the arrangement of a torpedo, which may preferably be of the loose loading type, in which the outstanding characteristics are neatness, cheapness of construction, and elimination of machinery processes. Broadly, the invention is exemplified in a container of any suitable material, such as paper, housing a powder charge, which, in the preferred instance is loosely packed, but which may be of a more solid form compacted with any conventional form of binder. This powder container, which is usually suitably water-proofed, but which is not necessarily so, is wrapped in a suitable water-proofed covering such as water-proof paper or the like.

A feature of the invention is that the powder container may be cut to such dimensions, that to secure the proper charge, it is merely necessary to fill the container with powder, without definitely measuring the charge in any other manner. An outer jacket or strip of material, substantially of the form illustrated in the accompanying drawings, is employed to retain the torpedo package formed in the above described manner. The torpedo package is laid on this strip of material, preferably with its longitudinal axis extending along the center line of the ears of the piece of material. A strap of metal such as lead, spring-steel or the like is employed to secure the torpedo to the jacket by means of a suitable adhesive or the like. The ears of the jacket are then folded about the track torpedo, after which the end of the jacket to which the strap is adhered is rolled end over end to secure the package and the strap in a closely assembled relation. The opposite end of the jacket, if desired, may have an adhesive applied thereto, whereby it may be secured to the body of the torpedo.

An object of the invention, therefore, is to produce a track torpedo of new and novel construction.

Another object is to produce a track torpedo characterized by its neatness, cheapness of construction, and elimination of machinery processes during its construction.

50 Another object is to produce a track tor-

pedo employing a container of such construction that the necessary charge may be determined by merely filling the container with powder.

Another object is to devise a novel method 55 of assembling a track torpedo.

Still another object is to produce a new form of jacket or piece of material for retaining the torpedo package of a torpedo in close proximity to a rail-engaging metallic strap. 60

Other objects will appear hereinafter.

In the drawings in which is illustrated one form of my invention;

Fig. 1 is a perspective view illustrating the powder container associated with its accompanying charge located upon its protective strip of material which, when in its assembled relation, produces the torpedo package illustrated in Fig. 2;

Fig. 2 is a perspective view illustrating 70 the torpedo package of Fig. 1, properly located upon a retaining jacket which is shown in its extended position;

Fig. 3 shows the next two steps of the assemblage, wherein the ears of Fig. 2 have been 75 folded over and about the torpedo package, and the rail-secured metallic strap is secured to one end of the jacket;

Fig. 4 is a view similar to Fig. 3, but illustrating the first rotation of the jacket end 80 over end to produce the result illustrated in Fig. 5, while

Fig. 5 shows the completed torpedo with the metallic strap in its extended position, the end of the jacket remote from the metal 85 strap being secured to the adjacent turn of the jacket by means of a suitable adhesive or the like.

At 1 is illustrated a container which may contain a suitable charge 2. This charge may preferably comprise loosely packed powder, but may be of a more solid form compacted with any conventional form of binder. An advantage resident in the use of this form of container resides in the fact that if the container has a properly selected volume, it is necessary merely to loosely fill it with the charge, whereby the proper quantity of powder may be determined without the necessity of any other method of measuring. As 100

shown, the container with its powder charge is placed on a sheet of paper or the like 3, preferably water-proofed in suitable manner, and being of substantially rectangular shape. This wrapping 3 is folded about the container in such manner as to produce the torpedo package indicated at 4 in Fig. 2.

The package thus assembled is then placed on a sheet of material 5 such as water-proofed paper or the like, preferably of rectangular shape, but having ears 6 and 7 formed along the longitudinal edges thereof. These ears preferably have the form of truncated triangles, the bases of which are substantially the same length as the longitudinal sides of the rectangular portion. As shown, the edge 8 of the jacket portion 5 may be of a slightly greater width than the opposite end 9, though this particular construction need not be followed necessarily. The outermost portions 10 and 11 of the ears 6 and 7 are then folded over upon the package 4 substantially in the manner indicated in Fig. 3, and the portions 10 and 11 are preferably slightly crimped.

26 During the folding process, the entire extent of the ears 6 and 7 are preferably folded over upon the rectangular mid-portion, substantially along the lines indicated at 12 and 13. At this time, a strip of lead, spring-steel, or other suitable material, indicated at 14, and preferably of relatively great length as compared to its width, is placed on the jacket 5 adjacent the end 8 thereof, and in the preferred form is secured thereto by means such as a suitable adhesive 15 or the like. The edge 8 is then rolled over as indicated in Fig. 4, and this wrapping process, end over end, is continued until the package, similar to that illustrated in Fig. 5, is produced. At this 40 time, the end 9 of the jacket 5 is preferably secured to the next adjacent turn by suitable means such as an adhesive 16 or the like.

A slightly modified form of assemblage is as follows: The jacket 5 is laid out, folded, 45 and the powder container 1, together with its charge of powder, is placed transversely thereof at approximately one inch distance from one of the transverse edges thereof, and is located substantially midway between the 50 longitudinal extremities. The longitudinal edges of the jacket adjacent the extremities of the powder container are then crimped up over the container, and with the crimps held in position by the operator's fingers, the jacket 55 is then folded about the container, beginning at the one end, for approximately one turn. The metal strap 14 is then preferably sealed to the exterior of the jacket adjacent the before-mentioned turn thereof, after 60 which the rolling process is continued for approximately two or three additional turns. The outer end of the jacket is then dipped in any suitable binder, after which it is adapted to seal the whole torpedo together, holding all 65 the apparatus in its relative position, and

resulting in a thoroughly water-proof torpedo. It is contemplated, however, that if desirable, the jacket 5 shall be coated on its interior surface with a suitable adhesive, so that it is merely necessary to moisten the same to cause it to adhere firmly to the torpedo package and the strap.

With the strip assembled in the manner indicated in Fig. 5, it is necessary only to shape the strap 14 to the head of the rail in order to place the torpedo in its operable position. The torpedo so produced is characterized by its safety and efficiency as a signal, simplicity and neatness of appearance, together with its extremely great strength, resulting from the constructional process employed. It is of course understood, that the jacket 3 may be omitted if desired and that numerous modifications can be made in the preferred process, without departing from the spirit of the invention. Accordingly, it is intended that the invention be limited only by the scope of the appended claims.

I claim:

1. In a track torpedo employing a torpedo package, an elongated piece of material adapted to be folded about and to retain said torpedo package, and a metallic strap adhering to one end of said strip of material, whereby the said package and the said strap, when the said strip of material is in its folded position, are in assembled relation to one another.

2. In a track torpedo, a torpedo package, and a substantially elongated strip of material having ear portions adapted to fit about and to retain said package and strap for securing the torpedo to a rail, the said piece of material being adapted to retain the said strap and the said package, when in their assembled relation, in close proximity to each other.

3. The method of assembling a track torpedo which comprises the steps of forming tapered ears along the longitudinal extremities of a substantially rectangular piece of material, placing a torpedo package transversely of the piece of material with its longitudinal axis substantially coincidental with that portion along the short axis of the strip of material of greatest width, folding the ear portions about the package, placing a metallic strap on the piece of material in proximity to the torpedo package, and folding the piece of material about the package and the strap to secure them in close proximity to each other.

4. The method of assembling a track torpedo which comprises the steps of forming tapered ears along the longitudinal extremities of a substantially rectangular piece of material, placing a torpedo package transversely of the piece of material with its longitudinal axis substantially co-incident with that portion along the short axis of the

strip of material of greatest width, folding the ear portions about the package, placing a metallic strap on the piece of material about the package and securing the loose end of the piece of material to the body portion by means of adhesive.

5. The method of assembling a track torpedo which comprises the steps of forming tapered ears along the longitudinal extremities of a substantially rectangular piece of material, placing a torpedo package transversely of the piece of material with its longitudinal axis substantially coincidental with that portion along the short axis of the strip 10 of material of greatest width, folding the ear portions about the package, and securing a metallic strap to one end of the said piece of material by means of an adhesive.

6. The method of assembling a track torpedo which comprises the steps of filling the 20 container of selected volume with a powder charge, sealing said container and charge with a strip of material, thus forming a torpedo package, placing the torpedo package 25 on a piece of material, placing a metallic strap on said torpedo in proximity to said package, and folding said piece of material about said package and said strap to secure them in close proximity to each other.

- 30 7. In a track torpedo, a spirally wound strip of material, a metallic strap secured at its center to the inner end of the material and having its ends projecting from the roll produced by winding the material, and a torpedo 35 package secured to the material intermediate the ends thereof.

8. In a track torpedo, a spirally wound strip 40 of material, a metallic strap secured at its center to the inner end of the material and having its ends projecting from the roll produced by winding the material, and a torpedo package secured to the material intermediate the ends thereof, the edges of the strip being folded back upon the torpedo package.

- 45 9. The method of assembling track torpedoes which comprises providing an elongated strip of material, attaching a metallic strap to one end of the material, attaching a torpedo package to the material intermediate its ends and then forming a spiral roll 50 from the material employing the end thereof which has the strap attached thereto as the inner end of the roll.

HUGH WILLIAMSON KELLY.
